UNITED STATES PATENT OFFICE.

NELS P. FLODIN, OF MARQUETTE, MICHIGAN, ASSIGNOR TO LAKE SHORE ENGINE WORKS, OF MARQUETTE, MICHIGAN, A CORPORATION OF MICHIGAN.

HOIST.

Application filed June 24, 1921. Serial No. 480,026.

To all whom it may concern:

Be it known that I, NELS P. FLODIN, a citizen of the United States, residing at Marquette, in the county of Marquette and State of Michigan, have invented certain new and useful Improvements in Hoists, of which the following is a specification.

This invention relates to a new and improved hoist, and more particularly to a hoist of the type having a plurality of independently operable drums. While it is broadly adapted for various uses, my improved hoist is especially designed for underground use in mines for moving ore or coal by the so-called scraper or slusher method. In this method of operation, the ore, instead of being loaded into cars and trammed to the desired point of delivery, is moved by a scraper or slusher broadly similar to the ordinary road scraper used in surface work for handling dirt in grading and excavating.

To meet the requirements for underground operation in mines, the hoist or other machine used to drag the scraper should be very powerful for its size and weight. It should be as small and as light as is practicable and so designed that the mechanism is entirely protected from entry of ore or dirt.

In order that the scraper may have sufficient capacity to move a reasonable amount of material upon each trip, it must be made so large and heavy that it is impractical to return it to the loading point by hand. Consequently two ropes are used, a hauling rope and a tail rope. The tail rope pays out from one winding drum while the hauling rope is being wound upon another drum. When drawing the scraper back to its loading position the winding is reversed.

In the operation of such hoists by means of electric power, it is highly desirable that the machine be so designed as to avoid the necessity for reversing the direction of rotation of the electric motor.

It is an object of the present invention to provide a hoist adapted for use in manipulating drags or scrapers of the character described.

It is a further object to provide a hoist which is light and strong, which is composed of but few and simple parts, and

which is capable of standing up under heavy loads.

It is also an object to provide a hoist provided with a plurality of drums which are independently operable and which may be freed from the power and permitted to pay out rope under braking control.

It is an additional object to provide a device of this character which is operated by a single lever.

Other and further objects will appear as the description proceeds.

My invention broadly comprises a plurality of hoist drums carried by a single shaft, the shaft being rotated in a constant direction, preferably by means of an electric motor. The drums are freely rotatable upon the shaft and clutch means are provided to selectively connect either drum to the shaft so that it may be rotated thereby. The clutch means for the two drums are operated by a single lever, the clutches being operatively connected by a shaft preferably contained within the main hoist shaft. Brakes are further provided in association with each drum, and in the preferred form these brakes are operated by means of the clutch operating lever.

I have illustrated a preferred embodiment of my invention in the accompanying drawings, in which—

Figure 1 is a side view partly in section showing the hoist and its associated motor;

Figure 2 is a sectional plan view taken upon the center line of the main hoist shaft, showing the clutch operating mechanism;

Figure 3 is an end view of the hoist; and

Figure 4 is a fragmentary section showing the clutch operating mechanism.

As best shown in Figure 1, the electric motor 5 is mounted upon the base 6, which is common to the entire hoist mechanism. The shaft 7 of the motor is provided with a pinion 8 which meshes with the pinion 9 carried by the hoist driving shaft 10. The shaft 10 is supported in the gland 12 and its outer end brings up against a thrust bearing 13. This shaft is provided with the worm 11 which meshes with the hoist gear wheel 14 carried by the main hoist shaft 15. The main shaft 15 is supported at either end in the supporting frames 39 and 46. The lateral thrust, due to the inter-action be-

tween the worm gear 11 and gear wheel 14, is taken care of by an end thrust bearing 58.

As best shown in Figure 2, the wheel 14 is keyed to the shaft 15. The worm 11 and wheel 14 are completely enclosed by the oil tight casing 16 and the pinions 8 and 9 are also protected by the casing 17.

Upon either side of the gear wheel and casing are located the drums 18 and 19. 10 These drums are freely rotatable upon the shaft. The two drums are provided with the inner clutch surfaces 20 and 21 and with the brake surfaces 22 and 23, respectively. Expanding friction clutches 24 and 25 of 15 usual construction are so located as to contact with the surfaces 20 and 21, respectively. The clutch 24 is operated by the links 26, the outer ends of these links being connected to the shifter sleeve 27. This sleeve 27 20 is adapted to move longitudinally upon the shaft 15 and is connected through that shaft by the key 28 to the clutch shifter shaft 29. This shaft 29 is contained within the shaft 15 and slides freely therein. A pair of 25 elongated slots 30 is formed in the shaft 15 to permit longitudinal movement of the key 28. The clutch 25 is operated by the links 31 which are connected to the shifter sleeve 32. This sleeve 32 is also connected 30 to the clutch shifter shaft 29 by a key 33 which passes through slots 34 in the shaft 15. The shifter sleeve 32 receives the shifter yoke 35, a bearing washer 36 being interposed between the members 32 and 35. 35 As best shown in Figure 4, the trunnions 37 of the yoke 35 are received in the jaws of the operating fork 38. This fork 38 is supported by the standard 39 and is movable about a pivot 40 which is located in 40 a plane transverse to that of the shaft 15. The fork 38 at one end is provided with the actuating quadrant 41 which has beveled gear teeth meshing with those upon a similar quadrant 42 carried upon the shaft 45. To this quadrant 42 is secured the operating lever 44.

Referring now to Figure 3, a shaft 45 is provided extending below the main shaft 15, the ends of the shaft being pivotally supported in the end frames 39 and 46. 50 This shaft is provided with the arm 47 which is fixedly connected thereto, and this arm is connected by the link 48 to the arm 49 connected to the operating lever 44. 55 The shaft 45 is also provided with the ear 50 to which is pivotally connected the brake rod 51. This rod 51 passes through the brake arm 53, and nuts 54 upon the end of the rod maintain the brake spring 55 against the brake arm 53. The brake arm 53 is provided with a brake lining 56 which bears upon the brake face 23 of the hoist drum 18. The brake 57 is similarly connected to the shaft 45 and bears upon the brake drum 22 of the hoist drum 18.

In the operation of my apparatus the motor 5 is put in motion in such direction as to rotate the shaft 10 and the gear wheel 14 in the directions indicated by the arrows in Figure 1. This power is transmitted 70 from the motor shaft 7 to the driving shaft 10 by means of the pinions 8 and 9, a certain amount of gear reduction taking place between pinions. The gear wheel 14 is rotated by the worm gear 11 and a quite considerable gear reduction is afforded by this drive. Thus the total gear reduction is such that a small, high-speed motor may be used 75 and the hoist drums may nevertheless be driven at a proper speed.

With the operating lever 44 in its neutral position both drums 18 and 19 are disconnected from the shaft 15. Further, the brakes 53 and 57 bear lightly upon the drums and prevent their free rotation. 80 When the lever 44 is moved to the right as seen in Figure 3, the fork 38 by means of the gear sectors 41 and 42 is so rotated about its axis as to move the shifter sleeve 32 to the left, as seen in Figure 2. This movement of the shifter sleeve 32 is transmitted to the shifter sleeve 27 by means of the shifter shaft 29 and the keys 33 and 28, but the movement of sleeve 27 in this direction simply serves to move the links 95 26 in such direction as to maintain the clutch 24 released. The movement of the shifter sleeve 32 serves to so operate the links 31 as to expand the clutch 25 and connect the hoist drum 19 to the shaft 15. 100 Simultaneously this movement of the lever 44 is transmitted to the shaft 45 by means of the arm 49, the link 48 and arm 47. The rocking motion of the lever 45 serves to so move the lug 50 as to push out the brake 105 rod 51 and release the spring 55, which fits against the brake arm 53. The braking action upon the hoist drum 19 is thus relieved. This same motion of the shaft 45 serves also to increase the spring pressure 110 upon the brake 57 and thus resists the rotation of the hoist drum 18 upon the shaft 15 sufficiently to prevent overrunning or backlash.

A reverse movement of the lever 44 115 through its central neutral position to the opposite end of its movement serves to release the clutch 25 from the hoist drum 19 and to apply the brake thereto, and further to so operate the clutch 24 as to connect 120 the hoist drum 18 to the shaft 15 and to release the brake on that hoist drum. In the neutral position, as has been stated, both hoist drums are disconnected from the shaft and are lightly braked to prevent play 125 or backlash.

In the particular utilization of my hoist, the drag rope will have its end connected to one drum and its opposite end to the front of the drag. The tail rope will be connected 130

to the other drum and will pass over a pulley fixed at the point of load and then will have its other end attached to the rear of the drag. The operation of the drag is entirely controlled by a movement of the single lever 44. Movement in one direction serves to draw the scraper forward; movement to neutral position halts it for discharge; and movement of the lever in the opposite direction causes the scraper to be hauled back to its loading point by the tail rope.

While the hoist has been shown as operated by the hand lever, it is obvious that this lever may have a rope or rod or other means connected thereto so that remote control may be had if desired. The brakes effectively prevent backlash or overrunning of the rope and are automatically operated by the operating lever. The braking action on the outgoing rope is not sufficiently heavy to materially add to the power required, but is simply sufficient to put a slight tension on the idle rope so as to take up slack and keep the rope slightly taut.

The particular form of driving connection which I have shown is of particular value not only in its compactness and its gear reduction but also because it readily adapts itself to the use of different motors of differing sizes. The spur gears 8 and 9 are all that need be changed to vary the gear ratio or to accommodate the hoist to the use of motors of different sizes or motors having their shafts at different elevations above the base. The spur gears also prevent transmission of any longitudinal motion from the motor shaft to the shaft carrying the worm gear.

My hoist is exceedingly compact in design, simple in construction and is composed of but few and rugged parts. The working parts are so placed as to minimize the dan-

ger of injury or derangement due to ore or other material working into the apparatus. 45

I claim

1. In a hoist mechanism, a driving shaft, a hollow driven shaft, a pair of hoist drums upon said driven shaft in spaced relation, said drums being rotatable independently 50 of each other and of the shaft, a clutch shaft in said hollow driven shaft, clutches operating upon each of said drums, clutch operating sleeves for each of said clutches fitted slidably upon the hollow shaft and 55 connected through slots in the shaft to the clutch shaft, a lever operatively connected to one of said clutch sleeves, brakes operating upon the drums, and means connecting said brakes to said lever, whereby movement 60 of the lever in either direction from an intermediate position serves to release the brake and throw in the clutch on one of said drums.

2. In a hoist mechanism, a driving shaft, 65 a hollow driven shaft, a pair of hoist drums upon said driven shaft in spaced relation, said drums being rotatable independently 70 of each other and of the shaft, a clutch shaft in said hollow driven shaft, clutches operating upon each of said drums, clutch operating sleeves for each of said clutches fitted slidably upon the hollow shaft and connected through slots in the shaft to the clutch 75 shaft, a lever operatively connected to one of said clutch sleeves, brakes operating upon the drums, and means connecting said brakes to said lever, whereby movement of the lever in either direction from an intermediate 80 position serves to release the brake and throw in the clutch on one of said drums, both brakes being partly applied when the lever is in said intermediate position.

Signed at Marquette, Michigan, this 17th day of June, 1921.

NELS P. FLODIN.
